ATTORNEYS

UNITED STATES PATENT OFFICE.

WALTER SURY, OF PROVIDENCE, RHODE ISLAND.

TOOL HOLDER.

Application filed November 26, 1920. Serial No. 426,515.

To all whom it may concern:

Be it known that I, WALTER SURY, a citizen of the United States, and a resident of Providence, in the county of Providence and 5 State of Rhode Island, have invented certain new and useful Improvements in Tool Holders, of which the following is a specification.

My invention is an improvement in tool 10 holders, and has for its object to provide a holder of the character specified, especially adapted for use with lathes and the like, for firmly holding the tool in any desired position and for inside or outside cutting.

15 In the drawings:

Figure 1 is a side view of the improved tool holder,

Figure 2 is a plan view,

Figure 3 is a view similar to Figure 1 20 of the body of the tool holder,

Figure 4 is a section on the line 4—4 of Figure 2,

Figure 5 is a view in section, on line 5—5 of Figure 1; and

25 Figure 6 is an edge and face view of one of the clamping nuts.

In the present embodiment of the invention, the improved holder comprises a body 1 of suitable cross section and length, having at one end a head 2 and at the head the body has a transverse opening 3. Intersecting this opening there are two bores 4 and 5, the bore 4 being at the axis of the body, while the bore 5 is inclined with respect to 30 the said axis, both bores opening at that end of the body which has the head.

These bores 4 and 5 are for receiving cutting tools, and referring to Figure 4 especially, it will be seen that the opening 3 40 intersects each bore. Within these openings there is arranged a collar 6 and a nut 7, respectively, which are of a size to fit within the opening, and to move freely in the said opening. The nut 7 is threaded while the 45 opening of the collar 6 is plain, and a screw 8 is passed through the opening of the collar 6 and threadedly engages the opening of the nut 7.

The nut and collar as will be evident from 50 an inspection of Figures 2 and 6 are knurled

on their peripheries for convenience in handling, and have upon their inner ends transverse grooves 9 and 10, respectively, which are adapted to register with and form continuations of, the bores 4 and 5. 55

When a tool is placed in either bore 4 or 5 the screw 8 is first loosened to permit the insertion of the tool, after which it is tightened to clamp the collar and nut on the tool, and to hold it firmly in place. By means 60 of the corrugations on the nut and collar, they may be turned to bring the grooves 9 and 10 into register with the bores 4 and 5.

A tool may be held by the improved holder to cut inside or outside. To cut inside or 65 outside, it is placed in the bore 5, and to cut a straight hole, it is placed in the bore 4.

I claim:

1. A tool holder of the character specified, having at one end a transverse opening and 70 inclined and axial bores intersecting the opening and extending transversely of the axis thereof, a nut and collar within the opening at opposite sides of the holder and grooved at the bores to form continuations 75 thereof, and means for drawing the nut and collar together to clamp them on a tool in the bore.

2. A tool holder of the character specified, having at one end bores converging to- 80 ward the end of the holder, and a common means for clamping a tool in either bore, said means comprising a nut and a collar, the holder having an opening in which the nut and collar are movable transversely of 85 the holder, and means for drawing the nut and collar together.

3. A tool holder of the character described having at one end bores converging toward the end of the holder, said tool holder hav- 90 ing an opening intersecting said bores, and common means operating in said opening for clamping a tool in either bore.

4. A tool holder having an axial bore and an inclined bore, said bores converging 95 toward the forward end of the tool, and means for clamping the tool in either bore.

WALTER SURY.
